SHOETREE

Michael S. Kissel, Pittsburgh, Pa.

Application April 1, 1939, Serial No. 265,422

2 Claims. (Cl. 12—129.1)

My invention relates to shoe-trees, particularly to shoe-trees of the sort that are applied externally upon the soles of the shoes that are to be straightened and held in shape, and consists in certain new and useful improvements in the structure of such devices.

A device embodying the invention is illustrated in the accompanying drawing, in which Fig. I is a view of the device in side elevation, in position of service upon the sole of a shoe; Fig. II is a view of the bottom of the shoe, showing the applied device in plan; and Fig. III is a view to larger scale, showing the device in perspective, in position to be applied to a shoe.

15. The device consists in a substantially flat body which, upon being secured to the bottom of a shoe, straightens and supports the sole of the shoe in such manner that the body of the shoe, distorted in service, is restored to and held in desired shape or form. The device includes means that marginally engage the sole at the toe, together with means that engage the sole at points adjacent to the heel of the shoe, the means last-mentioned consisting essentially in a clamp. 20 Hitherto, it has been found practical and desirable to form the body of such devices principally of steel wire, and in exemplary way I form my device of such material.

Referring to the drawing the shoe-straightening device consists in a body formed of two limbs 1 and 2 fashioned of steel wire and integrated in spaced-apart relation, as shown, by means of a rectangular disk or web 3 of sheet metal. Integration of the parts may be effected by welding or soldering, but in this case I show the side edges 3a of the web wrapped and securely crimped upon the wire bodies of the limbs. The body of the web may be corrugated or embossed to provide greater strength and rigidity, and to such end I 25 form ribs 3b in the body of the web.

Extending forward from the web 3 (extending to the left of the web in Fig. III), the two limbs 1 and 2 carry, or are formed into, means for securing the device to the sole S at the toe, and said two limbs, extending to the rear of the web 3, form the two arms of a clamp that is adapted to engage the opposite edges of the sole at the instep of the shoe. In this case, I form the two limbs 1 and 2 of a single reach of wire that is bent medially of its length into the form of a U; the wire is shaped at the bend into a catch portion 4 that, vertically offset (by portions 5) from the plane of the U, is adapted marginally to engage the sole S, as shown in Fig. I. The catch 4

provides the means alluded to for securing the device to the sole at the toe of the shoe.

The portions of the limbs 1 and 2 extending rearward from the web 3 (extending to the right of the web in the drawing) are flexible, and by virtue of such flexibility such portions of the limbs may be moved relatively to one another, as the arms of a clamp or a pair of tongs may be moved. The distal ends of the limbs or legs are offset from the plane of extent of the limbs, and are bent inward, providing tips 6 which, equipped with small knobs 7, are adapted to be closed and secured upon the opposite edges of the sole S. More specifically, the bodies of the limbs 1 and 2 are so shaped adjacent to their distal ends that they extend upward (in portions 8) from said plane, then outward (in portions 9), and upward again (in portions 10) to the sole-engaging tips 6. Thus, the tips 6 are offset from the plane of the legs 1 and 2 by an interval equal to the sum of the lengths of the two portions 8 and 10. By virtue of the particular form and organization of the component parts, the sole S of the shoe, upon application of the device, is drawn to and secured in proper position, and the body of the shoe is prevented from warping and becoming distorted.

I shall now turn to a consideration of the means in which the invention is centered—the means for securing the ends 6 of the limbs 1 and 2 in closed position upon the edges of the sole. Such means consist, advantageously, in a pivoted or hinged member which is adapted to be moved angularly of the plane of the limbs 1 and 2 between limb-locking and limb-releasing positions. More particularly, such means consist in a U-shaped member 12 that is hinged at the two ends of the U to the body 1, 2 of the device. Referring particularly to Fig. III, it will be perceived that, immediately inward from the sole-engaging ends of the two limbs 1, 2, the limbs severally include portions 13 and 14 that lie in common plane with the main portions of the limbs, that is to say, the portions that are engaged and integrated by means of the web 3. The portions 13 extend angularly to one another in such plane, and the portions 14, severally extending outward from the portions 13 to the main reaches of the limbs 1 and 2, provide pintle portions about which the ends of the U-shaped member 12 are coiled, as at 17, to provide the desired hinge attachment. It is further important to note that the body of member 12 at its outer or distal end (the body portion of member 12 at the base of the U) is bent from the plane of the two legs of the U, 55

providing two angular portions 15 that are adapted laterally to engage the inclined portions 13 and thereby secure the legs or arms 1, 2 in clamped or closed position of service upon the shoe.

Extending between the portions 15, the basal portion 16 of the U provides a handle that is accessible for ready manipulation of the member 12. When the shoe-tree is applied, the portion 16 lies at an interval below the sole of the shoe and below the convergent leg portions 13, so that it may be readily grasped between the fingers, and the member 12 swung downward and outward into release position.

One thing more is to be particularly noted. The parts are so formed and proportioned that, when the shoe-tree is being closed upon a shoe, the parallel legs or sides of the locking member 12 bear upon the inclined portions 13, 13 of the limbs 1 and 2, with the consequence and effect that, as the U-shaped member 12 moves angularly, under applied pressure into locking position, the two legs of the U operate with progressive wedging effect upon the portions 13, 13, forcing such portions towards one another and swinging the limbs 1 and 2 inward, and thus shifting the tips 6 into ultimate clamping position upon the sole of the shoe. When the legs of the locking member 12 reach a position of parallelism with the limbs 1, 2 (Fig. I), the portions 13, 13 (with the tips 6, 6 tightly engaged on the edges of sole S) are positioned and secured between the portions 15, 15 of the member 12. The shoe-tree is locked in position of service.

It will be noted that the pintle portions 14, 14 of the limbs 1, 2 are of substantial length transversely of the structure, and that the body portions of the limbs at the ends of such pintle

portions serve to limit the range of the tong-like movement of the limbs. When the limbs 1, 2 are moved, the pintle portions shift axially within the hinge-eyes 17 of the locking member 12.

I claim as my invention:

1. In a device of the class described consisting in a body provided with a catch adapted marginally to engage the sole of a shoe at the toe and including a clamp adapted to engage such sole adjacent to the heel of the shoe and thereby secure said body in shoe-straightening engagement with such sole, which clamp includes two clamping arms and means for securing the arms in said engagement with the shoe; the refinement herein described in which said means comprise a member including two spaced-apart portions adapted laterally to engage and secure said arms in clamp-closing position, said member being mounted to swing angularly to the plane of the sole, upon which the device is applied, between clamp-closing and clamp-releasing positions.

2. In a shoe-tree including a body provided with two limbs or arms movable as the arms of a pair of tongs and shaped at their distal ends to engage a shoe, and a device for locking said arms in shoe-engaging position; the refinement herein described in which said tong-like arms include pintle portions and inclined portions, and in which said locking device comprises a U-shaped member pivoted at the ends of the legs of the U to said pintle portions and movable angularly into such position that the legs of the U engage said inclined portions of the tong-like arms with wedging effect, to press said arms into secure position between said legs of the U.

MICHAEL S. KISSEL.
